J. W. TAYLOR

PUMPING APPARATUS FOR OIL WELLS

Filed July 9, 1923

UNITED STATES PATENT OFFICE.

JAMES W. TAYLOR, OF SAN ANTONIO, TEXAS.

PUMPING APPARATUS FOR OIL WELLS.

Application filed July 9, 1923. Serial No. 650,409.

To all whom it may concern:

Be it known that I, JAMES W. TAYLOR, a citizen of the United States, residing at San Antonio, in the county of Bexar and 5 State of Texas, have invented certain new and useful Improvements in Pumping Apparatus for Oil Wells, of which the following is a specification, reference being had to the accompanying drawings.

10 This invention relates to pumping apparatus for oil wells and more particularly to devices of this character in which oil is forced from the well by the pressure of air or gas.

15 Specifically, the principal object of the invention is to provide an improved valve structure for use in oil well pumping apparatus of the type disclosed in the co-pending application of myself and Alexander J. 20 Taylor, for improvements in pumping apparatus for oil wells, filed June 6, 1923, Serial No. 643,652. In this application we have disclosed an apparatus including valves which upon vertical shifting of the 25 flow line successively open or close to establish communication at various points along the flow line between the flow line and the casing within which it is located. While the valve disclosed in this application is 30 operative the cost of producing the same is excessive and furthermore a tight joint, such as is necessary in this type of apparatus is difficult to maintain. Accordingly, an important object of this invention is the provision of a valve of this character which 35 may be very cheaply produced, which affords a tight seal at all times and which is generally an improvement upon the structure of the valve set forth in such co-pending application.

40 A further object of the invention is to provide an attachment for the valve whereby the air admitted to the flow line by the valve is directed along the walls of the flow line in a thin stream, it having been found that this form of air admission is the most effective in elevating the fluid within the flow line.

45 These and other objects I attain by the construction shown in the accompanying drawings, wherein for the purpose of illustration is shown a preferred embodiment of my invention and wherein:—

50 Figure 1 is a partially diagrammatic view, parts being in section and parts in elevation, showing pumping apparatus includ-

ing valves constructed in accordance with my invention;

55 Figure 2 is a longitudinal sectional view taken through the valve, the same being shown in the open position;

60 Figure 3 is a similar view showing the valve in the closed position assumed when the valve is closed by elevation of the pipe line;

65 Figure 4 is a similar view showing the valve in the closed position assumed when the valve is closed by lowering of the flow line; and

70 Figure 5 is a horizontal sectional view taken through the valve on the line 5—5 of Figure 2.

75 Referring now more particularly to the drawings, the numeral 10 indicates the casing of a well and 11 a flow line disposed within the casing. The flow line 11 comprises a plurality of sections 12 connected by control valves 13 for controlling the admission of air or gas contained within the casing to the flow line. The lowermost section 12 of the flow line is provided with a foot screen and valve structure, generally indicated at 15, and which may be of any desired construction but which is preferably of the same construction set forth in 80 the co-pending application hereinbefore mentioned.

85 The flow line is sealed to the casing, as generally indicated at 16, adjacent the upper end thereof, the seal permitting vertical movement of the flow line within the casing 10. Below the seal 16 a fluid pressure inlet 17 is provided through which pressure may be introduced to the casing to enter the flow line through the valves 13 hereinbefore indicated. At the upper end of the casing

90 means are provided, generally indicated at 18, for lifting the flow line and the flow line is provided, as at 19, with means adjustably limiting the lowering thereof. The 95 construction of the lifting and limiting means herein illustrated is generally shown as identical with that of the co-pending application hereinbefore mentioned and will 100 not accordingly be specifically described since any suitable apparatus of this character may be provided.

105 The valves 13 each embody upper and lower sleeve members 20 and 21, each formed of hard steel. The sleeve 20 or upper sleeve is provided at its lower end with an enlargement 22 forming an inwardly directed

shoulder 23 at the upper end thereof, this shoulder being disposed at an angle of approximately 35°. The upper end of the sleeve 20 is integrally screw-threaded, as indicated at 24, for a purpose presently to appear. The lower end of the lower sleeve member 21 is externally screw-threaded for engagement with a coupling 25 by means of which it is connected with the flow pipe section 12 therebelow. The upper end of the sleeve member is provided with an enlargement 26, the ends of which are rounded as indicated at 27, the lower rounded end confronting and coacting with the beveled shoulder 23 formed by the enlargement 22.

The threaded upper end of the upper sleeve 20 engages with a hard steel coupling member 28, the lower face of which is beveled, as indicated at 29, oppositely to the bevel of the shoulder 23 of the sleeve 20. The internal diameter of this coupling is the same as that of the casing sections 12 and the upper end of the coupling member has its bore enlarged and integrally screw-threaded, as at 29a, for the reception of the lower end of the casing section above the valve. The internal diameter of the sleeve 21 is slightly less than the internal diameter of the casing sections 12 and the upper end of this sleeve is internally screw-threaded, as indicated at 30, for the reception of an extension nozzle 31, the lower end of which is beveled, as at 32, to prevent the formation of abrupt shoulders interfering with the flow through the flow line. The upper end of this sleeve in all positions of the lower sleeve members extends above the upper end of the valve, as represented by the upper end of the coupling member 28, and projects into the lower end of the uppermost of the casing sections 12 which the valve connects.

In the construction of the device the internal diameter of the sleeve 20 at the enlargement 22 is made slightly greater than the external diameter of the sleeve 21 proper, and the internal diameter of the sleeve 20 proper is made slightly greater than the external diameter of the sleeve 21 at the enlargement 26. The enlargement 26 of the sleeve 21 is made of a length less than the distance between the lower end 29 of the coupling member 28 and the shoulder 23 of the sleeve 20. Similarly, the extension nozzle 31 has an external diameter slightly less than the internal diameter of the coupling member 28 and accordingly of the flow pipe sections 12 with which it is associated. In the operation of the device it will be obvious that by elevation of the flow line the valves will be successively opened and closed and by lowering of the flow line they will be successively opened and closed. Assuming the flow line to be in its lowermost position, each valve 13 has the upper end of the en-

largement thereof in engagement with the lower end 29 of the coupling member 28. When lifting of the flow line is started the lower end of the coupling member 28 and the rounded upper end 27 of the enlargement 26 of the uppermost valve will separate, thus permitting fluid pressure to pass between the enlargement 22 of the sleeve and the sleeve 21, between the curved face 27 at the lower end of the enlargement 26 and the inclined shoulder 23, between the face of this enlargement and the adjacent face of the sleeve 20, and between the curved upper end 27 of the enlargement 26 and the lower end 29 of the coupling 28, and between the outer wall of the extension nozzle 31 and the inner face of the coupling member and the flow pipe section 12. Thus a thin stream of air under pressure may be admitted to the flow line and directed along the walls thereof. As the upward movement of the flow line continues the shoulder 23 will come into engagement with the curved lower face of the enlargement 26, with the result that the passageway above described is sealed at this point and communication cut off. At the same time opening of the valve 13 next below is started and this process is repeated at this valve and at each succeeding valve as the elevation continues. In lowering of the flow line the operation of the valves is reversed, the lowermost valve first opening and then closing and this process being continued through the series of valves. It will, of course, be obvious that by providing a suitable indicating means, such as disclosed at I, it may be readily determined which of the valves is open and the opening of the valves thus made positive. I do not claim the use of this indicating means as set forth and claimed in the co-pending application of myself and Alexander J. Taylor, above specified.

It has been found in practice that the use of soft metal for forming seats in valves of this character is impossible for the weight to be supported is tremendous and a seat which is formed of soft metal soon becomes deformed and useless. By the use of hard steel sections and the round shoulders upon the enlargements 26 coacting with the beveled faces 23 and 29, it has been found that a perfect seat can be formed and that this seat increases in efficiency in use. It will, of course, be obvious that certain change and modification in the structure can be resorted to without in any manner departing from the spirit of my invention and I accordingly do not limit myself to such specific structure as hereinbefore set forth except as herein-after claimed.

I claim:

1. A flow line for wells comprising a plurality of longitudinally movable sections and valves connecting adjacent ends of the

- sections, each valve including an upper sleeve provided at its lower end with an upwardly directed shoulder, the lower sleeve provided at its upper end with an 5
enlargement operating within the upper sleeve, and a coupling member engaging the upper end of the upper sleeve and having its lower end confronting the shoulder thereof, said coupling member and lower sleeve 10
member being adapted for connection with adjacent ends of casing sections, said enlargement having the opposite ends thereof rounded for engagement with confronting shoulders of the coupling member and upper 15
sleeve member.
2. A flow line for wells comprising a plurality of longitudinally movable sections and valves connecting adjacent ends of the sections, each valve including an upper sleeve 20
provided at its lower end with an upwardly directed shoulder, the lower sleeve provided at its upper end with an enlargement operating within the upper sleeve, and a coupling member engaging the upper end of the 25
upper sleeve and having its lower end confronting the shoulder thereof, said coupling member and lower sleeve member being adapted for connection with adjacent ends of casing sections, said enlargement having the opposite ends thereof rounded for engagement with confronting shoulders of the coupling member and upper sleeve member, said lower sleeve member being provided with an extension at its upper end directed 30
through the coupling member and of less diameter than the internal diameter of the coupling member.
3. A flow line for wells comprising a plurality of longitudinally movable sections and valves connecting adjacent ends of the sections, each valve including an upper sleeve provided at its lower end with an upwardly directed shoulder, the lower sleeve provided at its upper end with an enlargement operating within the upper sleeve, and a coupling member engaging the upper end of the upper sleeve and having its lower end 45
- confronting the shoulder thereof, said coupling member and lower sleeve member being adapted for connection with adjacent ends 50
of casing sections, said enlargement having the opposite ends thereof rounded for engagement with confronting shoulders of the coupling member and upper sleeve member, said confronting shoulders being oppositely beveled and spaced apart a distance greater than the length of the enlargement of the lower sleeve. 55
4. A flow line for wells comprising a plurality of longitudinally movable sections and valves connecting adjacent ends of the sections, each valve including an upper structure and a lower structure, each of said lower and upper structures being adapted for engagement with an end of a casing section, one of said structures having an enlargement provided with rounded end portions, the other of said structures affording opposed oppositely beveled shoulders spaced apart a distance greater than the length of 60
the enlargement of the other structure and between which said structure operates. 65
5. A flow line for wells comprising a plurality of longitudinally movable sections and valves connecting adjacent ends of the sections, each valve including an upper structure and a lower structure, each of said lower and upper structures being adapted for engagement with an end of a casing section, one of said structures having an 70
enlargement provided with rounded end portions, the other of said structures affording opposed oppositely beveled shoulders spaced apart a distance greater than the length of 75
the enlargement of the other structure and between which said structure operates, the lower structure of each valve including an upwardly extending nozzle directed through and of less diameter than the portion of the upper structure which it opposes. 80
85

In testimony whereof I hereunto affix my signature.

JAMES W. TAYLOR.
